ATTYS.

UNITED STATES PATENT OFFICE.

EDWARD SNYDER, OF CLEVELAND, OHIO.

DESIGN FOR A MOTOR-FAN CASING.

No. 39,419.

Specification for Design.

Patented July 14, 1908.

Application filed April 4, 1908. Serial No. 425,285. Term of patent 14 years.

To all whom it may concern:

Be it known that I, EDWARD SNYDER, a citizen of the United States, residing at Cleveland, in the county of Cuyahoga and State of Ohio, have invented a new, original, and ornamental Design of a Motor-Fan Casing, reference being had to the accompanying drawings, forming part thereof.

In the accompanying drawings, the single figure represents a perspective view of the design.

The salient features of the design thus shown are found in the hub ornamented with beads about its respective edges, and the

shape of the arms starting from the body thereof and terminating alike at one side wholly outside of the plane of the hub transversely and surmounted by an approximately flat ring, the whole constituting a motor fan casing of original conception and ornamental design.

What I claim is:—

The ornamental design of a motor fan casing as shown.

EDWARD SNYDER.
